SMOKE BOX ASSOCIATED DRAFT CONTROL
APPARATUS

Robert R. McIntosh, Battle Creek, Mich.

Application September 21, 1943, Serial No. 503,234

17 Claims. (Cl. 110—157)

1

The present invention relates broadly to pressure regulation, and in its specific phases it relates more particularly to the regulation of suction pressures in a locomotive smoke box wherein the pressure of the exhaust from the locomotive cylinders through an exhaust orifice of a suction inducing nozzle is controlled, and such controlled pressure in turn is utilized to automatically control, at least over a portion of its range of operation, an apparatus for regulating the upper suction pressures in the smoke box.

It has long been standard practice in connection with steam driven locomotives to deliver all, or substantially all, of the exhaust steam from the cylinders through an exhaust stand in the locomotive front end, and out of the smoke stack to create induced suction pressure in the smoke box and draft through the locomotive to promote combustion in the fire box. The back pressure thus created in the exhaust stand normally increases approximately in step with the increase of steam exhausted, and with some locomotives this normal back pressure rises to as high as approximately twenty-five pounds per square inch gage. The induced draft produced in this manner varies approximately in step with the back pressure in the exhaust stand, and with the high back pressures this induced draft is extreme. In order to reduce the detrimental effect in the fire box of the upper level of the suction pressure created in this manner, it has been standard practice to install baffles, partition plates, and netting in the smoke box, and to place a long ignition arch in the fire box. The extent to which this procedure can be satisfactorily carried is limited due to its adverse effect on the lower range of suction pressures, i. e. the greater the baffling, the greater is the amount of steam which must be exhausted to create the minimum required suction pressure for efficient and adequate combustion. High suction pressures produced in this manner under normal operating conditions not only reduce the combustion efficiency of the locomotive but also interfere with the uniform burning of the fire bed. Under high suction pressures, and particularly pulsating high suction pressures, the products of combustion carry an excessive amount of abrasive material from the fire box through the fire tubes and smoke box, and this in turn rapidly wears out the stay bolt heads, superheater units, smoke stack extension, and other parts which come in contact with the flow of products of combustion. Three ways of improving the drafting of a railway locomotive are set forth in my copending patent

5 applications Ser. No. 381,290, filed March 1, 1941, which has matured into Patent No. 2,379,916, dated July 10, 1945; Ser. No. 428,262, filed Jan. 26, 1942, which has matured into Patent No. 2,377,895, dated June 12, 1945; and Ser. No. 461,665, filed October 12, 1942. Those patent applications deal with multiple pressure level draft regulation through the use of one or more air inlet valves in the smoke box. One way to control back pressure on the locomotive cylinders, and incidentally modify suction pressure levels in the smoke box, is set forth in my copending patent application Ser. No. 441,095, filed April 30, 1942, which has matured into Patent No. 2,395,973, dated March 5, 1946. A study of the shortcomings, difficulties, and misconceptions of the prior art lead to the discovery and development of the present invention wherein, in preferred form, an air inlet means is cooperatively connected with an exhaust back pressure controlling mechanism so as to vary the air inlet pressure over a considerable range approximately in step with variations in exhaust back pressure.

Accordingly, among the objects of the present invention is the provision of an improved method and apparatus for controlling suction pressures.

Another object is to provide means for holding suction pressures in a railroad locomotive smoke box in a substantially continuous variable range normally approximately at or just above the suction pressure required for highly efficient combustion.

Another object is to provide a method and apparatus for admitting air in controlled amount into a locomotive smoke box when a predetermined suction pressure has been reached therein, and to automatically control such admission of air substantially in step with variations of the back pressure level of the locomotive cylinders as controlled by the back pressure governor.

A further object is to provide a suction pressure controlling apparatus which may be arranged to operate at various prechosen constant or variable ratios to the amount of steam passing through the locomotive cylinders or the like.

A further object is to reduce slagging of the fire tubes and tube sheet at the fire box end of the locomotive.

A further object is to provide an apparatus for controlling the back pressure of exhaust steam delivered from locomotive cylinders, an air inlet apparatus for controlling the upper level of the suction pressures in a locomotive smoke box, and means for connecting said back pressure controlling apparatus to said air inlet apparatus in

manner such that the two of them cooperate in more efficiently controlling the suction pressures in the locomotive smoke box.

Still further objects and advantages will appear as the description proceeds.

To the accomplishment of the foregoing and related ends, the invention, then consists of the steps and means hereinafter fully described and particularly pointed out in the claims, the annexed drawings and the following description setting forth in detail certain means and modes of carrying out the invention, such disclosed means and modes illustrating, however, but several of the various ways in which the principle of the invention may be used.

In said annexed drawings:

Figure 1 is a diagrammatic sectional front elevation of a locomotive smoke box showing a preferred form of the present invention as viewed along line 1—1 of Figure 2, looking in the direction of the arrows.

Figure 2 is a fragmentary diagrammatic side elevation of a locomotive front end with part of the smoke box shell broken away to show a preferred form of the present invention in place.

Figure 3 is a sectional side elevation of a preferred form of back pressure regulating apparatus as taken along line 3—3 of Figure 4 looking in the direction of the arrows.

Figure 4 is a top view of a preferred form of back pressure regulating apparatus as viewed along line 4—4 of Figures 2 and 3 looking in the direction of the arrows.

Figure 5 shows one form of valve guide cage suitable for use particularly as shown in Figures 3 and 7.

Figure 6 is a sectional center elevation of a preferred type of the piston and cylinder assembly which is diagrammatically shown in place in Figures 1 and 2.

Figure 7 shows a fragmentary vertical central elevation of a preferred form of the pressure relief valve assembly shown in place in the general assembly illustrated in Figures 1 and 2.

A preferred form of apparatus for carrying out the present invention is diagrammatically shown in the assemblies of Figures 1 and 2. Reference to those figures shows that there is a special form of exhaust stand 2 mounted within the smoke box for the purpose of controlling the exhaust steam back pressures. Also mounted in the smoke box is an air inlet apparatus 3 for controlling the upper ranges of the suction pressures therein. Exhaust stand 2 and air inlet apparatus 3 mutually aid each other and cooperate in producing uniform operating conditions, although in preferred construction they are suitably connected together so as to more closely control the suction pressure in smoke box 1 in accordance with prechosen variations in suction pressure which preferably follow draft requirements quite closely.

The exhaust stand 2 has an upwardly and outwardly flared lower portion 4 which extends upward to a substantially horizontal partition 5 above which is chamber 6, and an auxiliary chamber 7. Partitions 8 and 9 (Figure 4) are used to separate and form two walls of these chambers 6 and 7. If desired, partitions 8 and 9 may be omitted and thus leave one large chamber. Horizontal partition 5 is provided with a series of valve seat members 10 with valves 11 cooperatively seating on same. In the top of the exhaust stand directly above each valve seat is provided an opening 12 into which is threaded-

ly mounted a plug 13. A valve cage 14 (Figures 3 and 5), which is of slightly larger inside diameter than the diameter of valve 11, rests on the outer edge of the top face of valve seat member 10 and extends up into opening 12. Plug 13, which threadedly engages opening 12, is adapted to contact the upper end of cage 14 and hold the cage tightly against the upper end of valve seat 10 in manner preventing same from working loose under conditions of use. The inner wall 15 of chamber 6 and auxiliary chamber 7 forms a vertical passageway for the normal upward delivery of exhaust steam which is utilized for creating suction pressure in the locomotive smoke box.

Nozzle 16 is mounted centrally above the passageway formed by inner wall 15 and is held in place in conventional manner. At the outlet end of nozzle 16 is preferably provided a spreader member 17 which is anchored in place and utilized to spread the exhaust steam so as to make a seal with the inner face of the smoke stack. The upper portion of nozzle 16 may be made hollow to form a blower ring 18 with a plurality of upwardly directed jets 19, and a live steam inlet pipe 20. Connected to chamber 6 are a pair of outlet pipes 21 and 22. Where an auxiliary chamber 7 is utilized, same will be provided with an outlet pipe 23. Valves 11 are preferably made of such size and weight relative to the area of opening in valve seat member 10 that they will remain in closed position until a prechosen back pressure has been created in expansion chamber 24 below horizontal partition 5. The valve then elevates to by-pass part of the exhaust steam and thus aid in maintaining the prechosen back pressure. The flaring of the exhaust stand to provide an expansion chamber 24 acts to expand and cushion the exhaust from the locomotive cylinders and make the flow of exhaust steam out of exhaust nozzle 16 more uniform. This is of a distinct aid in promoting relatively uniform suction pressures in the smoke box at different rates of steam exhaust from the locomotive cylinders.

Mounted in the upper portion of the smoke box, preferably in front of smoke stack 25, are a pair of tubular inlet members 26 and 27 (Figure 1) which are joined to a center tubular member 28 in substantially air-tight manner according to conventional practice. At the inlet end of members 26 and 27 are respectively mounted closure gates 81 and 82 which are movable endwise on slide members 83 and 84. The closing of these gates renders the air inlet apparatus inoperative and permits the making of repairs to same without interfering with the use of the locomotive. The upper face of tubular member 28 is provided with flanged opening 29, which is preferably circular. Mounted in the upper portion of tubular member 28 is a cross member 30 carrying a suitable bearing 31 substantially central of opening 29. Slidably fitting bearing 31 is a vertically mounted shaft 32 of suitable length which carries valve disc 33 anchored thereto in conventional manner. In order to make disc 33 slide up and down without rotary action, guide pins 85 and 86 (Figure 1) may be joined thereto and slidably fit suitable openings in cross member 30. Valve disc 33 in turn is provided with packing 34 which is adapted to seat on the upper flanged face of tubular member 28 outside of opening 29. This packing 34 may be optionally mounted on the upper flanged face of tubular member 28 in position to seat on the under face 75 of valve disc 33, and the drawing is intended to

diagrammatically illustrate either type of construction. The upper end of shaft 32 extends through a suitable opening in a removable pan member 35 which is preferably flanged and conventionally connected to a suitable flanged member 36 extending in air-tight manner upward from the top of smoke box 1. Mounted on pan 35 is a plate member 37 on which is mounted a cylinder 38 (Figure 6) with upper and lower cylinder heads 39 and 40. Shaft 32 extends through the lower cylinder head 40 in conventional manner and has a piston 41 mounted on the upper end thereof. To facilitate this, shaft 32 is provided with a rounded knob end 42 connected to shaft 32 by means of a short reduced diameter extension member 43. The use of a rounded knob end connection for the piston facilitates alignment of the piston in the cylinder, and also the removal of the piston from the top of the cylinder for cleaning or other purposes. Piston 41 has an opening through its upper end which is of a sufficient size to permit the passage of knob end 42 therethrough. The extension member 43 in this case should be long enough to permit knob end 42 to be passed sufficiently through the hole in the upper end of piston 41 so that a suitably slit or multiple-piece ring 44 can be placed under knob end 42 in recess 45. A cap 46 shaped to fit knob end 42 is then tightened down in place to the body 47 of piston 41 by means of cap screws 48, or the like, with sufficient clearance to permit movement of the knob end for alignment of the piston in the cylinder. Upper cylinder head 39 is preferably provided with a threaded opening 49 adapted to threadedly engage pipe 50 for a purpose to be hereinafter described. In order to reduce frictional loss the piston is preferably provided with circumferential grooves 87 which fill with liquid to produce a piston ring effect. A drain 88 in lower cylinder head 40 is provided to permit escape of any liquid which by-passes piston 41.

Connected to the expansion chamber 24 of exhaust stand 2 is a suitable connection 51 to which is threadedly joined a nipple 52. A ground joint coupling 53 connects nipple 52 to pipe 54 which extends to a pipe T 55, one outlet from which is connected to pipe 50 at the top of cylinder 38 by means of nipple 56, ground joint coupling 57, pipe 58, elbow 59, pipe 60, elbow 61, pipe 62, elbow 63, nipple 64, ground joint coupling 65, pipe 66, and elbow 67. The second outlet from pipe T 55 may be closed if desired, and in that case, any increase or decrease in back pressure in expansion chamber 24 of exhaust stand 2 will directly vary the pressure exerted on the top of piston 41 in cylinder 38 and thus directly affect the loading of valve disc 33 with corresponding variation of the suction pressure in the smoke box at which valve disc 33 will open to admit a suction reducing gaseous fluid such as air. The ratio of loading the valve disc 33, and consequently the rate of increase in the suction pressure controlled by the disc can be varied by varying the size of cylinder 38, i. e. a given rise in back pressure in expansion chamber 24 will produce increased loading of the disc when the cylinder is larger.

If a controlled upper pressure is to be exerted on the top of piston 41 in cylinder 38, a thing which will substantially prevent further increase in the suction pressure in the smoke box, a suitable pressure relief assembly 68 (Figures 1, 2 and 7) may be used. The construction of this pressure relief assembly is as follows: Pipe T 55 is 75

connected by means of pipe 69 to the bottom of housing 70 (Figure 7) of pressure relief assembly 68. In preferred construction, housing 70 is provided with a partition 71 forming a chamber 72 in the bottom of pressure relief assembly 68. Threadedly fitting a suitable opening through partition 71 is a valve seat member 73 which cooperates with valve 74 to form a closed joint at pressures in chamber 72 below a prescribed level. This pressure is predetermined and valve 74 made of a suitable weight to start rising when this pressure is reached in chamber 72. A valve cage 75, which may be made of the same general construction as valve cage 14 shown in Figure 5, is adapted to pass through a suitable opening 76 in the top of housing 70. This opening is preferably threaded and a plug 77 utilized to close same, and at the same time hold valve cage 75 against the top of valve seat member 73 to prevent same from coming loose under conditions of use. Nipple 78, ground joint coupling 79, and nipple 80 serve to connect the interior of relief assembly 68 to the atmosphere, and for convenience nipple 80 may be connected to outlet pipe 22 for outlet therethrough of any steam which flows into the upper portion of housing 70 due to the raising of valve 74 from valve seat member 73 under influence of steam pressure in chamber 72.

The back pressure in expansion chamber 24 may be relatively closely governed by predetermined the weight of valves 11. The valves 11 in chamber 6 may be all of the same weight, if desired, a thing which will produce a substantially single upper pressure level for the back pressure in expansion chamber 24 of the exhaust stand. Any increase of the amount of steam exhausted from the locomotive cylinders 89 will require a correspondingly greater generation of steam. This in turn calls for increased draft suction pressure which can be accomplished by varying the weight of valves 11 so that some will open at a prescribed back pressure and others will open at a higher back pressure or pressures, thus giving a gradual rise in back pressure in expansion chamber 24 as the valves become progressively subjected to steam pressures in excess of their capacity to control. Auxiliary chamber 7, where same is utilized, may be adapted to go into operation under certain prescribed conditions, and may have valves therein set to meet a prescribed back pressure situation. For instance, they may act as overload valves to hold the back pressure in expansion chamber 34 from rising above a prescribed upper level. A valve 90 may be connected to outlet pipe 23, and this valve may be used to permit or prevent any exhaust flow from auxiliary chamber 7.

In actual operation, the maximum and minimum draft requirements for a locomotive are predetermined and then the weight of valve disc 33, shaft 32, guide pins 85 and 86, and piston assembly 41 are adjusted so that valve disc 33 will start to raise and admit suction reducing air into smoke box 1 through opening 29 at the point where the desired minimum operating suction pressure has been reached. The raising of the back pressure incident to increased steam consumption will cause fluid pressure to be exerted through the pipe connections to the top of piston assembly 41 and thus additionally load valve disc 33 and increase the suction pressure in the smoke box according to a predetermined ratio, preferably in step with the increased steam generation requirements.

This arrangement permits the reduction of the

discharge orifice area in nozzle 16 substantially below the area normally used so that a relatively small amount of exhaust steam discharged through the nozzle will create the minimum back pressure desired and produce relatively higher suction pressures and provide for efficient combustion even under low steam demand conditions. From this point on the valves in the exhaust stand control the back pressure in accordance with a predetermined plan so that with increased steam consumption the back pressure will increase at a predetermined rate and thus effect in like manner the loading of disc 33 as previously explained. Such loading may thus be varied to agree with a predetermined range of suction pressures which will meet the requirements of drafting the locomotive. Controlling suction pressures in this manner not only makes possible highly efficient operation so far as combustion, and increased mean effective pressures on the driving cylinders are concerned, but it also decreases slagging of the tubes and the fire box tube sheet. The latter advantage, it is believed, is due to the fact that suction pressures, when utilizing the present invention, are readily held at the minimum predetermined level even under light operating conditions, and this in turn provides sufficient draft to maintain higher temperatures in the fire box while reducing or substantially eliminating the clinkering and fusing of the ash in the fire bed as a result of the more constant and increased flow of air therethrough. Then by controlling the upper suction pressures so as to be just slightly in excess of the maximum required for efficient combustion, the possibility of increased suction pressures causing the carrying of molten slag, if any is produced, over the arch and against the tube sheet, to which it will promptly adhere and eventually plug over the tube openings on the fire box end, is materially reduced. The absence of violent pulsations in the flow of the products of combustion, due to the use of the back pressure governor and air inlet apparatus in the smoke box, materially contributes to this result.

Other modes of applying the principle of my invention may be employed instead of those explained, change being made as regards the means and steps herein disclosed, provided those stated by any of the following claims or their equivalent be employed.

I therefore particularly point out and distinctly claim as my invention:

1. In an apparatus of the character described, the combination which comprises walls forming a chamber wherein pressure is to be controlled, an inlet thereto, an outlet therefrom, means having a passageway of fixed size flow area for directing a gaseous fluid flowing under pressure out through said outlet to produce suction pressure in said chamber by injection effect, self-contained means adjacent said passageway and within the confines of said chamber for controlling the upper pressures of said gaseous fluid in said means for delivering same through said outlet from said chamber, means for admitting suction reducing gaseous fluid into said chamber when the suction pressure produced therein by the flow of controlled pressure fluid directed through said outlet exceeds a predetermined amount, and pressure responsive means connecting said means for delivering a gaseous fluid through said outlet to said means for admitting suction reducing gaseous fluid into said chamber so as to vary the gaseous fluid admission over the latter, over at least a substantial range of its op-

eration, approximately inversely to pressure variations in the former.

2. In an apparatus of the character described, the combination which comprises walls forming a chamber wherein pressure is to be controlled, an inlet thereto, an elongated outlet member extending from the interior to the exterior of said chamber, means having a passageway of fixed size flow area for directing a gaseous fluid flowing under pressure out through said elongated member in manner such that said gaseous fluid forms a circumferential seal with the inner surface of said elongated outlet member and produces a suction pressure in said chamber by injection effect, self-contained means adjacent said passageway and within the confines of said chamber for controlling the upper pressures of said gaseous fluid in said means for delivering same through said outlet means from said chamber, means for admitting suction reducing gaseous fluid into said chamber when the suction pressure produced therein by the flow of controlled pressure fluid directed through said outlet exceeds a predetermined amount, and pressure responsive means connecting said means for delivering a gaseous fluid through said elongated member to said means for admitting suction reducing gaseous fluid into said chamber so as to vary the gaseous fluid admission of the latter, over at least a substantial range of its operation, approximately inversely to pressure variations in the former.

3. In an apparatus of the character described, the combination which comprises walls forming a chamber in which a reduced pressure exists, an inlet thereto and an outlet therefrom, a duct communicating with a source of higher pressure fluid, said duct having an outlet into said chamber, a valve for said outlet, a cylinder, a piston in said cylinder, means for connecting said piston to said valve for movement in unison therewith, and means connected to said cylinder for applying a second fluid under pressure to said piston in controlled amount for determining the opening point of said valve which maintains a controlled upper limit of fluid pressure in said chamber.

4. An apparatus for controlling pressure in a walled chamber, which comprises an inlet and an outlet from said chamber, means for forcibly delivering a gaseous fluid out through said outlet to produce reduced pressure in said chamber by injection effect, means for controlling the pressure in said gaseous fluid delivering means, means having a valve for admitting suction reducing gaseous fluid into said chamber when the suction pressure therein exceeds a predetermined amount, and means including a cylinder with piston and a tubular member connecting said cylinder to said gaseous fluid delivering means, the piston of said cylinder being conventionally connected to the valve of said means for admitting suction reducing gaseous fluid into said chamber, whereby the pressure in said first gaseous fluid delivering means is used to vary the opening of said valve for admitting suction reducing gaseous fluid into said chamber with resultant control of the pressure therein at which said suction reducing gaseous fluid is admitted thereto.

5. An apparatus for controlling pressure in a walled chamber, which comprises an inlet means, an elongated tubular outlet member extending from the interior to the exterior of said chamber, means for forcibly delivering gaseous fluid

out through said elongated outlet member in manner such that said gaseous fluid forms a circumferential seal with the inner surface of said elongated outlet member and produces a suction pressure in said chamber by injection effect, means for controlling the pressures in said means for delivering gaseous fluid through said outlet means from said chamber, means having a valve for admitting suction reducing gaseous fluid into said chamber when the suction pressure therein exceeds a predetermined amount, and means including a cylinder with piston and a tubular member connecting said cylinder to said gaseous fluid delivering means, the piston of said cylinder being conventionally connected to the valve of said means for admitting suction reducing gaseous fluid into said chamber, whereby the pressure in said first gaseous fluid delivering means is used to vary the opening of said valve for admitting suction reducing gaseous fluid into said chamber with resultant control of the pressure therein at which said suction reducing gaseous fluid is admitted thereinto.

6. An apparatus for controlling pressure in a walled chamber, which comprises an inlet means for flow of fluid into said chamber, an elongated tubular outlet member extending from the interior to the exterior of said chamber, means for forcibly delivering gaseous fluid out through said elongated outlet member in manner such that said gaseous fluid forms a circumferential seal with the inner surface of said elongated outlet member and produces a suction pressure in said chamber by injection effect, means for controlling the pressures in said means for delivering gaseous fluid through said outlet means from said chamber, means for admitting suction reducing gaseous fluid into said chamber when the suction pressure therein exceeds a predetermined amount, said gaseous fluid admitting means including an inlet duct, with outlet therefrom, a valve disc for closing said outlet, a cylinder, a piston in said cylinder, and means for connecting said piston to said valve disc in manner permitting movement of said valve disc to and from said outlet, and means for connecting said gaseous fluid delivering means to said cylinder of said means for admitting suction reducing gaseous fluid into said chamber, whereby the pressure in said gaseous fluid delivering means is used to control the pressure in said chamber at which said suction reducing gaseous fluid is admitted thereinto.

7. An apparatus for controlling pressure in a walled chamber, which comprises an inlet means for flow of fluid into said chamber, an elongated tubular outlet member extending from the interior of the exterior of said chamber, means for forcibly delivering gaseous fluid out through said elongated outlet member in manner such that said gaseous fluid forms a circumferential seal with the inner surface of said elongated outlet member and produces a suction pressure in said chamber by injection effect, means for controlling the pressures in said means for delivering gaseous fluid through said outlet means from said chamber, said pressure controlling means including at least one valve which opens to divert part of said gaseous fluid when the fluid pressure in said means for forcibly delivering gaseous fluid out through said elongated outlet member exceeds a predetermined level, means for delivering said diverted portion of said gaseous fluid to a point of disposal, whereby the pressure in said means for forcibly delivering gaseous fluid is

controlled, means for admitting suction reducing gaseous fluid into said chamber when the suction pressure therein exceeds a predetermined amount, and means connecting said gaseous fluid delivering means to said means for admitting suction reducing gaseous fluid into said chamber, whereby the pressure in said gaseous fluid delivering means is used to control the pressure in said chamber at which said suction reducing gaseous fluid is admitted thereinto.

8. An apparatus for controlling pressure in a walled chamber, which comprises an inlet means for flow of fluid into said chamber, an elongated tubular outlet member extending from the interior to the exterior of said chamber, means for forcibly delivering gaseous fluid out through said elongated outlet member in manner such that said gaseous fluid forms a circumferential seal with the inner surface of said elongated outlet member and produces a suction pressure in said chamber by injection effect, means for controlling the pressures in said means for delivering gaseous fluid through said outlet means from said chamber, said pressure controlling means including at least one valve which opens to divert part of said gaseous fluid when the fluid pressure in said means for forcibly delivering gaseous fluid out through said elongated outlet member exceeds a predetermined level, means for delivering said diverted portion of said gaseous fluid to a point of disposal, whereby the pressure in said means for forcibly delivering gaseous fluid is controlled, means for admitting suction reducing gaseous fluid into said chamber when the suction pressure therein exceeds a predetermined amount, said gaseous fluid admitting means including an inlet duct with outlet therefrom, a valve disc for closing said outlet, a cylinder, a piston in said cylinder, and means for connecting said piston to said valve disc in manner permitting movement of said valve disc to and from said outlet, and means for connecting said gaseous fluid delivering means to said cylinder of said means for admitting suction reducing gaseous fluid into said chamber, whereby the pressure in said gaseous fluid delivering means is used to control the pressure in said chamber at which said suction reducing gaseous fluid is admitted thereinto.

9. An apparatus for controlling draft through a railroad locomotive having driving cylinders, a smoke box, a smoke stack extending therefrom, a fire box, and passageways for delivering smoke from the fire box to the smoke box, which comprises the combination therewith of means with a fixed area passageway for delivering steam exhausted from said driving cylinders out through said smoke stack to create induced suction pressure in said smoke box, self-contained means within the confines of said smoke box for controlling the upper pressure of said exhaust steam in said delivering means before delivery therefrom, means for admitting a suction reducing gaseous fluid into said smoke box when the suction pressure produced therein by the flow of controlled pressure exhaust steam directed through said outlet reaches a predetermined level, and pressure responsive means connected to said exhaust steam delivery means and to said suction reducing gaseous fluid admitting means for varying the pressure level at which said suction reducing gaseous fluid is admitted to said smoke box so that over a considerable range of operation it is directly in step with variations in

the upper pressure of said exhaust steam in said delivering means.

10. In a railroad locomotive which has driving cylinders, a smoke box, an inlet and an outlet from said smoke box for products of combustion, a governor for the exhaust back pressure on the driving cylinders, and a valve controlled inlet to said smoke box for a suction pressure reducing gaseous fluid, the combination which includes a variable loading means connected to said valve covering the suction pressure reducing gaseous fluid inlet to said smoke box, and pressure responsive means connected to said back pressure governor and to said variable loading means for varying the loading of said inlet valve directly in step with variations in the governed exhaust back pressure.

11. An apparatus for controlling draft through a railroad locomotive having driving cylinders, a smoke box, a smoke stack extending therefrom, a fire box, and passageways for delivering smoke from the fire box to the smoke box, which comprises the combination therewith of means for delivering steam exhausted from said driving cylinders out through said smoke stack to create suction pressure in said smoke box, means for controlling the pressure of said exhaust steam in said delivering means, a valve controlled inlet to said smoke box for a suction pressure reducing gaseous fluid, a cylinder with piston and piston rod, said rod being connected to said valve, and tubular means for operatively connecting said means for delivering exhaust steam into and through the smoke stack to the cylinder connected for variably loading the valve of said means for admitting suction reducing gaseous fluid into said smoke box, said connecting means utilizing the pressure in said exhaust steam delivering means to control the suction reducing gaseous fluid admitting means so that it admits suction reducing gaseous fluid into said smoke box when the suction pressure therein is in excess of a predetermined level.

12. An apparatus for controlling draft through a railroad locomotive having driving cylinders, a smoke box, a smoke stack extending therefrom, a fire box, and passageways for delivering smoke from the fire box to the smoke box, which comprises the combination therewith of means having a passageway of fixed size flow area for delivering steam exhausted from said driving cylinders out through said smoke stack to create suction pressure in said smoke box, valve means adjacent said fixed size flow area passageway for controlling the pressure of said exhaust steam therein by bleeding off a portion of same under conditions where the exhaust steam back pressure exceeds a predetermined minimum, means for delivering said bleed-off portion to a point of disposal, means for admitting a suction reducing gaseous fluid into said smoke box when the suction pressure therein reaches a predetermined level, said means for admitting a suction reducing gaseous fluid including an inlet duct with outlet therefrom into said smoke box, and a movable valve disc for closing said outlet, said valve disc having a variable loading means so that said valve may elevate from said outlet and admit a controlled amount of suction reducing gaseous fluid into the smoke box under predetermined suction pressure conditions therein, and means connected to said fixed area passageway and to said variable loading means for variably loading the latter directly in step with pressure variations in said fixed area passageway.

13. An apparatus for controlling draft through a railroad locomotive having driving cylinders, a smoke box, a smoke stack extending therefrom, a fire box, and passageways for delivering smoke from the fire box to the smoke box, which comprises the combination therewith of means having a passageway of fixed size flow area for delivering steam exhausted from said driving cylinders out through said smoke stack to create suction pressure in said smoke box, valve means adjacent said fixed size flow area passageway for controlling the pressure of said exhaust steam therein by bleeding off a portion of same under conditions where the exhaust steam back pressure exceeds a predetermined minimum, means for delivering said bleed-off portion to a point of disposal, means for admitting a suction reducing gaseous fluid into said smoke box when the suction pressure therein reaches a predetermined level, said means for admitting a suction reducing gaseous fluid including an inlet duct with outlet therefrom into said smoke box, and a valve disc for closing said outlet, said valve disc being suitably loaded so as to open said outlet and admit a suction reducing gaseous fluid into the smoke box under predetermined suction pressure conditions, a cylinder with piston and piston rod, said piston rod being connected to said valve disc for further loading same in variable manner, and tubular means for connecting the fixed area passageway of said gaseous fluid delivering means to the cylinder connected to said valve means for admitting a suction reducing gaseous fluid into said smoke box, whereby the pressure of the exhaust steam in said means for delivering exhaust steam through the smoke stack is used through said connecting means to control the suction pressure in said smoke box at which said means for admitting suction reducing fluid opens to admit suction reducing gaseous fluid thereinto.

14. An apparatus for controlling draft through a railroad locomotive having driving cylinders, a smoke box, a smoke stack extending therefrom, a fire box, and passageways for delivering smoke from the fire box to the smoke box, which comprises the combination therewith of means for delivering steam exhausted from said driving cylinders out through said smoke stack to create suction pressure in said smoke box, valve means for controlling the pressure of said exhaust steam in said delivering means by bleeding off a portion of same under predetermined conditions, means for delivering said bleed-off portion to a point of disposal, means for admitting a suction reducing gaseous fluid into said smoke box when the suction pressure therein reaches a predetermined level, said means for admitting a suction reducing gaseous fluid including an open end inlet duct with outlet therefrom, a valve disc for closing said outlet, a cylinder, a piston in said cylinder, and means for connecting said piston to said valve disc in manner permitting and controlling the movement of said valve disc to and from said outlet, and means for connecting said exhaust steam delivering means to said cylinder of said means for admitting suction reducing gaseous fluid into said chamber, whereby the exhaust steam pressure in said exhaust steam delivering means is used to control the pressure in said chamber at which said suction reducing gaseous fluid is admitted thereinto.

15. An apparatus for controlling draft through a railroad locomotive having driving cylinders, a smoke box, a smoke stack extending therefrom, a fire box, and passageways for delivering smoke

from the fire box to the smoke box, which comprises the combination therewith of means for delivering steam exhausted from said driving cylinders out through said smoke stack to create suction pressure in said smoke box, valve means for controlling the pressure of said exhaust steam in said delivering means by bleeding off a portion of same under predetermined conditions, means for delivering said bleed-off portion of said exhaust steam to a point of disposal, means for admitting a suction reducing gaseous fluid into said smoke box when the suction pressure therein reaches a predetermined level, said means for admitting a suction reducing gaseous fluid including an inlet duct with outlet therefrom, a valve disc for closing said outlet, a cylinder, a piston in said cylinder, and means for connecting said piston to said valve disc in manner permitting and controlling the movement of said valve disc to and from said outlet, and a tubular means connected to said exhaust steam delivering means at one end and to said cylinder at the other, whereby variations in pressure in said exhaust steam delivering means will be transmitted to and applied on said piston which in turn, through its connection to said valve disc, will vary the loading on the latter and will correspondingly vary the suction pressures in the smoke box at which same will open.

16. An apparatus for controlling draft through a railroad locomotive having driving cylinders, a smoke box, a smoke stack extending therefrom, a fire box, and passageways for delivering smoke from the fire box to the smoke box, which comprises the combination therewith of means for delivering steam exhausted from said driving cylinders out through said smoke stack to create suction pressure in said smoke box, valve means for controlling the pressure of said exhaust steam in said delivering means by bleeding off a portion of same under predetermined conditions, means for delivering said bleed-off portion of said exhaust steam to a point of disposal, means for admitting a suction reducing gaseous fluid into said smoke box when the suction pressure therein reaches a predetermined level, said means for admitting a suction reducing gaseous fluid including an inlet duct with outlet therefrom, a valve disc for closing said outlet, a cylinder, a piston in said cylinder, and means for connecting said piston to said valve disc in manner permitting and controlling the movement of said valve disc to and from said outlet, a tubular means connected to said exhaust steam delivering means at one end and to said cylinder at the other, whereby variations in pressure in said exhaust steam delivering means will be transmitted to and applied on said piston which in turn, through its connection to said valve disc, will vary the loading on the latter and will correspondingly vary the suction pressures in the smoke box at which same will open, and valve means connected to said tubular means for predetermineding the upper limit of pressure which will be applied to said piston.

17. An apparatus for controlling draft through a railroad locomotive having driving cylinders, a smoke box, a smoke stack extending therefrom, a fire box, and passageways for delivering smoke from the fire box to the smoke box, which consists of the combination therewith of an exhaust stand, means for conducting exhaust steam from said cylinders to said exhaust stand, said exhaust stand having an expansion space, a substantially central upwardly directed passageway, a nozzle at the outlet end thereof, a chamber around said upwardly directed passageway, a substantially horizontal bottom panel for said chamber, a series of valve seat members in said bottom panel, a valve of predetermined size in said chamber for each of said valve seat members, means for guiding said valves to and from said valve seat members, and outlet connections from said chamber; means for admitting air into said smoke box when the suction pressure therein reaches a predetermined level, said air inlet means consisting of a relatively large duct normally open to the atmosphere at least at one end and provided with a substantially horizontal outlet on its upper face, a valve disc for said outlet, means for making a substantially tight fit between said disc and the upper face of said duct when said disc is in place over said outlet, a rod on which said disc is fastened, guide means for said rod, means for guiding said disc in a longitudinal direction, a cylinder, means on which said cylinder is mounted, a piston in said cylinder, said piston being fastened on one end of the rod on which the valve disc is fastened; and a tubular means connecting the expansion space of the exhaust stand to said cylinder, whereby any increase in pressure in the expansion space will increase the pressure in the cylinder and thus increase the loading on the valve disc with consequent increase in the suction pressure in said smoke box at which the valve disc will elevate and admit suction reducing air thereinto.

Certificate of Correction

Patent No. 2,479,502

August 16, 1949

ROBERT R. McINTOSH

It is hereby certified that error appears in the printed specification of the above numbered patent requiring correction as follows:

Column 7, line 74, for the words "over the" read *of the*;
and that the said Letters Patent should be read with this correction therein that the same may conform to the record of the case in the Patent Office.

Signed and sealed this 17th day of January, A. D. 1950.
